UNITED STATES PATENT OFFICE.

YOSHIO MATSUMURA, OF MINAMI-KATSUSHIKA-GUN, TOKYO, JAPAN.

APPARATUS FOR SEARCHING AND LOCATING SUBAQUEOUS MATTER BY WAY OF SWEEPING.

1,305,483.

Specification of Letters Patent. Patented June 3, 1919.

Application filed February 20, 1919. Serial No. 278,111.

To all whom it may concern:

Be it known that I, YOSHIO MATSUMURA, a subject of the Emperor of Japan, and a resident of No. 624 Horikiri, Minami-Katsushika-Gun, Tokyo, Empire of Japan, have invented new and useful Improvements in Apparatus for Searching and Locating Subaqueous Matter by Way of Sweeping, of which the following is a specification.

10 This invention relates to apparatus employed for the purpose of searching and locating subaqueous matter by means of what is generally called "sweeping" with more particular reference to method of 15 spreading the range of the sweeping angle by means of a novel construction of device which I will term "spreader" adapted to be dragged along the sea surface. Heretofore in such apparatus in which the spreading 20 devices are kept below water surface the latter besides being equipped with necessary attachments have been accompanied with several additional appliances so as to keep same in proper position at desired depth of 25 water, consequently when towing operations begin the heavy resistance of the gear on the spreaders counteracts their sweeping efficiency. With my improvements this is overcome, as the spreader which is novel in 30 construction, as will appear later, serves itself as an efficient floater.

The object of the invention is to provide an arrangement of spreading device such that the latter will have to be dragged by 35 one vessel along the sea surface thereby considerably reducing the amount of resistance to towage.

A further object of the invention is to provide a spreader which will act in place 40 of otter boards for trawling nets.

A further object of the invention is to provide a spreading device which will work in surface water allowing the observation of the proper operation of the apparatus there- 45 by minimizing the chance of loss of or damage to the apparatus when caught on dangerous objects such as mines and the like.

Still further object of the invention is to provide an apparatus which will eliminate 50 the use of cumbersome floats and sinkers such as are necessary in the ordinary sweeping apparatus where the spreading appliances have to behave below surface water, thus permitting the use of lighter and less ex-

pensive appliances and generally to obtain 55 greater efficiency and facilities in working.

Another object of the invention relates to construction of the self extending spreaders and operation of parts, all of which will be clearly set forth in the following descrip- 60 tion.

In the accompanying drawings, illustrating the invention:-

Figure 1 is a perspective view of my improved-spreader, showing the same attached 65 with suspending bails and held in condition ready for towing.

Fig. 2 is a transverse sectional view taken on line A—A of Fig. 1.

Fig. 3 is a longitudinal sectional view 70 taken on line B—B of Fig. 1.

Fig. 4 is a diagrammatical view showing the apparatus in operation.

Referring now to the drawings the 75 spreader which is hollow and which is a sub- stantially flattened ellipse in cross section has forwardly curvated head portion C and backwardly tapered body portion D so as to assume the form somewhat resembling to the shape of the fish or torpedo.

In the outer casing 1 of this fish like member or spreader an inner similarly shaped but correspondingly smaller casing 2 is inclosed in such a manner as to leave an air space between both walls of the inner and 80 outer casing, thus dividing the interior of the spreader into air and water chambers 3, 4, respectively.

Upon one side of the spreader and approximately at the point of the largest 90 diameter of the head portion C thereof is provided an inlet opening 6 through which water rushes into the water chamber 4 when placed in working position upon the sea surface as will be more fully described herein- 95 after.

The inner wall of the inlet opening 6 is preferably inclined at a certain angle toward the head C and is provided along its mouth with semi-circularly flaring guide lip 100 7, likewise inclined toward the head, so that the inrushing water entering through the inlet will be caused to strike against the inner concave wall E of the inner casing 2 before flowing out from the exit 8.

Secured to and arranged at above and below and on both sides of the inlet 6 is a ring 9 to each of which is attached the lower end

of the bail 10, preferably adjusted to suit the circumstances, while the other end of each bail is gathered together and secured to the eye 11 which is adapted to receive the outer end 5 of the warp 14 to enable the spreader to be drawn along the sea surface in the manner shown in Fig. 4.

Fig. 4 illustrates the apparatus in operation, wherein 12 is the stern portion of the 10 tow vessel having on both sides a suitable bit 13, from each of which is paid out a towing warp 14, preferably tarred rope, adapted to connect with respective spreader through the medium of the bails 10, each spreader 15 being held in position with its inlet facing toward the stern of the vessel in operation while the exits point toward each other.

The function of the spreader is obvious that when the towing begins the mass of 20 water rushing through the relatively larger inlet 6 first impinges against the concave wall E of the water chamber 4, thence driven backward in the direction indicated by arrows until it eventually rushes out at considerable speed through the relatively 25 smaller exit 8. The effect is such that by reason of the reaction resulting therefrom both spreaders are forced to move along the plane of their longitudinal axis to such an extent 30 as to diverge themselves from each other so that each of the spreader ropes 15 which is preferably tarred and which is secured to the lower face of the spreader through the medium of the depending bails 10' and rings 9' 35 will be equally diverged from each other to such extent as to stretch between them the sweeper rope 17 which I prefer to be made of flexible steel wire, extending between and connecting the foot or weighted 40 end 16 of the respective spreader rope 15.

With this improved arrangement especially in view of the novel construction and peculiar contour of the spreader it will be obvious that the latter will perform their 45 proper function much more efficiently than such devices as hitherto adopted while there will also result a considerable saving in expense and labor.

What I claim is:—

1. A sweeping apparatus comprising a 50 plurality of spreaders, preferably fish shaped and substantially flattened ellipse in cross section, an inlet and outlet on said spreader respectively at head and tail portion thereof, means to cause the inrushing 55 water to strike against the head of the spreader before making its way to the exit.

2. A sweeping apparatus as set forth in claim 1, comprising an inner and outer casing, an air and water chambers formed between both casings and within the inner casing respectively.

3. A sweeping apparatus as set forth in claim 1, comprising an inlet having its wall inclined toward the head of the spreader 65 with equally inclined flaring lip extending half way along the mouth of the said inlet adapted to force the water toward the head of the spreader.

4. In a spreading device for sweeping apparatus as claimed in claim 1 the inlet opening having larger diameter than the outlet opening.

5. In a spreading device for sweeping apparatus as claimed in claim 1, a plurality of 75 suspending attachments arranged along the inlet opening and adapted to receive outer end of the towing warp, and a plurality of depending attachments secured to the lower face of the spreader adapted to connect with 80 spreader rope at the end most remote from the weighted end.

6. In a sweeping apparatus as claimed in claim 1, a pair of spreaders, each towed by separate warp with the head pointing oppositely to each other, a pair of ropes depending from each spreader, the sweeper ropes extending between and connecting both depending ropes.

In testimony whereof I affix my signature 90 in presence of two witnesses.

YOSHIO MATSUMURA.
